(57) CLAIM

The ornamental design for an abdominal support belt for pregnant women, as shown and described.

DESCRIPTION

FIG. 1 is a front view of an abdominal support belt for pregnant women, showing my new design exploded for clarity of disclosure;

FIG. 2 is a top perspective view of the upper strap of the abdominal support belt for pregnant women of FIG. 1;

FIG. 3 is a bottom perspective view thereof;

FIG. 4 is a front view thereof;

FIG. 5 is a rear view thereof;

FIG. 6 is a left side view thereof;

FIG. 7 is a right side view thereof;

FIG. 8 is a top view thereof;

FIG. 9 is a bottom view thereof;

FIG. 10 is a top perspective view of the lower strap of the abdominal support belt for pregnant women of FIG. 1;

FIG. 11 is a bottom perspective view thereof;

FIG. 12 is a front view thereof;

FIG. 13 is a rear view thereof;

FIG. 14 is a left side view thereof;

FIG. 15 is a right side view thereof;

FIG. 16 is a top view thereof;

FIG. 17 is a bottom view thereof; and,

FIG. 18 is a perspective view of the abdominal support belt for pregnant women of FIG. 1, shown in condition of use for clarity of disclosure.

The broken line showing of a human figure in FIG. 18 depicts environmental subject matter and forms no part of the claimed design.

1 Claim, 18 Drawing Sheets
